UNITED STATES PATENT OFFICE.

MIKE VARGO, OF YUKON, PENNSYLVANIA, ASSIGNOR OF ONE-HALF TO JACK F. YANNACCI, OF YUKON, PENNSYLVANIA.

CUE TIP.

Application filed February 14, 1923. Serial No. 618,948.

To all whom it may concern:

Be it known that I, MIKE VARGO, a citizen of Hungary, residing at Yukon, in the county of Westmoreland and State of Pennsylvania, have invented new and useful Improvements in Cue Tips, of which the following is a specification.

This invention relates to cue tips.

One of the main objects of the invention is to provide simple and efficient means for securing tips on cue sticks. A further object is to provide means whereby the tip and associated parts are effectually braced so as to prevent breakage of the tip or the securing means therefor from the stick. Another object is to provide means of the character stated which may be readily applied at small cost. Further objects will appear from the detailed description.

20 In the drawings:—

Figure 1 is an elevation of the tip securing means;

Figure 2 is a fragmentary central sectional view through the tip securing means;

25 Referring to Figures 1 and 2, the end portion of cue stick 1 is cut to provide an inner dowel 2 of less diameter than the end of stick 1, and an outer dowel 3 which is concentric with, and of less diameter than,

dowel 2. This provides a double dowel construction which snugly receives a plug 4 of ivory, or any other suitable or preferred material, which is secured in a brass ferrule 5 in any suitable or preferred manner. Plug 4, when of ivory or other hard material, is provided in its upper face with a plurality of concentric grooves adapted for reception of a suitable cement for securing a tip 6 on the upper end of the plug. An opening 7 is provided through the upper end of plug 4 and provides a flow hole for any excess cement.

30 What I claim is:—

In combination, a cue stick provided at its outer end with two concentric securing elements the inner one of which is of less diameter than the diameter of the stick, the outer one of said elements being of less diameter than the inner element, a ferrule, an ivory plug secured in said ferrule and fitting snugly about the securing elements, the inner end of the ferrule contacting with the cue stick at the inner end of the inner securing element, and a cue tip secured on the outer end of said plug.

35 40 45 50 55 In testimony whereof I affix my signature.

MIKE VARGO.
